FAGIN & HAYMAN.

Mill Bolt.

No. 8,025.

Patented April 8, 1851.

Inventors:
Lewis Fagin.
Henry C. Hayman

UNITED STATES PATENT OFFICE.

L. FAGIN AND H. C. HAYMAN, OF CINCINNATI, OHIO.

APPARATUS FOR BOLTING FLOUR.

Specification of Letters Patent No. 8,025, dated April 8, 1851.

To all whom it may concern:

Be it known that we, LEWIS FAGIN and HENRY C. HAYMAN, both of the city of Cincinnati and State of Ohio, have jointly invented new and useful Improvement in Bolting Flour or other Pulverized Material; and we do hereby declare the following to be a full, clear, and exact description of the same, reference being had to the annexed 10 drawings, making part of this specification, in which—

Figures 1, 2 and 3 give such representations of the same as may be readily understood by persons skilled in this branch of 15 industry.

The application of a blast of air to grinding or bolting purposes is not new as reference to several patents granted by the United States will readily show. The difficulty in bolting lies in the mode of application and we have after many practical experiments jointly discovered and invented the mode and means of this application.

It is obvious that a blast of air must be 25 continuous or else a blast cannot be maintained. It is also well known to millers that the bolting cloth is least effective when its meshes are under a continuous heavy feed. This is the reason why the meal has 30 been forced through the meshes of the bolting cloth by brushes but without satisfactory results, and we have found the same difficulty, in a more objectionable form resulting from the application of a blast of 35 air upon the entire surface of the bolting cloth, to wit: that the meshes of the cloth would fill up and the bolting cease. The reason of this is that after the first impulse 40 of the blast the meal packs in the meshes, under the continuous pressure of the blast.

The economy with regard to machinery and time occupied in bolting and the superiority of the flour manufactured under the atmospheric grinding and bolting processes have been tried and admitted by millers. The object remaining was to apply these processes in the best way. Referring to Lewis Fagin's Patent dated 30th October 1849 for improvements in grinding we 45 confine ourselves here to the enumeration of our joint invention and improvements in bolting, the practical difficulties in which are met in their order and overcome by the said improvements.

It is first necessary to supply the meal and this is done by the hopper (A) Fig. 1,

which drops the feed down the tube (B) to the openings (C) in the frame of the bolting machine, which openings (C) lead to the top of the blast-cylinder (E) and 60 through the space (D) between the cylinder and its frame to the space (F) between the blast-cylinder and bolting cloth (P). The feed being on and the blast applied a portion of the flour is instantly bolted, 65 when from the packing of and the increased proportion of the bran to the meal commingled with it, there is a necessity for beating the offal at a suitable distance adown the range of the machine. This we 70 effect by inserting a ring of beaters (G) instead of continuing the bolting-cloth, putting the beaters also on the blast-cylinder and thus for a time interrupting the bolting to give place to the process of loosening the remaining flour from the bran. This being 75 effected, the bolting process is resumed and continued until the finest and best flour, which is known to be closest to the bran, is made to yield its hold and pass through the 80 bolting cloth.

To effect the bolting of flour in the most economical way and obtain the greatest yield, we have found that it is necessary to give so much of the meal (which while 85 under the impulse of the blast, does not pass through the bolting cloth but has a tendency to clog its meshes) an interval of time during which the law of gravity compels the meal to fall from the meshes and be 90 prepared for another percussion from the air-blast as each succeeding current or issue of the blast meets it while thus dropping down the chamber or space (F). We have also found that it is desirable to disturb the 95 position of the leaf of bran as often as possible and thus give each leaf of the bran the chance of striking the bolting-cloth with its broad surface and thus avoid the specking of the flour. It is also desirable to protract the drop of the meal as long as possible; because it is best to use the most compact machine. All these things we effect by causing the blast to issue from spiral mouths (O) passing from top to bottom 100 of the blast cylinder (E) between the air tight spaces (3, 3, 3,) whether the blast is produced by vanes within the blast cylinder or by a separate fan forcing the air therein as the cylinder with the spiral issue 105 revolves, say 1,000 revolutions per minute more or less. The number of issues neces-

sary are determined by the diameter of the blast cylinder used. They should however be sufficiently far apart to allow of suitable intervals during which so much of the flour and bran as sticks may fall off from the bolting cloth. This spiral division of the blast into currents has (through the eddies it causes) a sort of loosening ripping up and twisting action, which is peculiarly effective in the bolting of the meal or flour. The blast being thus made to issue as it were on small and detached portions of the bolting cloth by means of the apertures (whether they run in a spiral line continuously from top to bottom of the cylinder or are made to consist of a series of short issues) an interval of time is gained between the action of succeeding issues upon any one portion of the bolting cloth, where by eddies are produced and the meal is allowed to relax its hold on and fall from the cloth and undergo a sort of refeeding to the impulse of the blast from the next issue.

Our bolting-machine has the receiving chamber (Q), delivering issues (R), collecting chamber (S), scraper (T) and spouts (U) and (H). The scraper (T) may be appended to a revolving tube (N) which is attached to the blast cylinder for the purpose of conducting the air whether forced in through the tubes (L) and stationary tube (M) by a fan (K) on the spindle (I) or drawn in by vanes on the blast cylinder itself. The amount of blast can be regulated in various ways.

We have also found that under atmospheric bolting it is necessary to provide against wastage of the material bolted; the light flour being liable to be carried off by the escaping blast, and it is obvious that this tendency to wastage must be counteracted and yet no detriment be done to the free escape of the blast. This we effect by placing over the bolting machine, proper, one or more chambers suitably closed at top for the eddying and lulling the blast, and catching the flour, and having an angular roof or sides inclining toward each other at top for the flour to drop from and slide down as it accumulates. These chambers are represented in Fig. 1 at (Y) and at (1). The chamber (Y) gathers its flour through the opening (X) and delivers the flour it gathers into a chamber below the openings (Z) and from this chamber the flour falls into the chamber (S') through the openings (&). The chamber (Y) follows the periphery of the top of the bolting machine and is of course circular. The chamber (1) is also circular and surrounds the feed tube (B). The first vent for the blast is at (V) where it is, as it were, partially intercepted by the inner side of the chamber (Y). The blast then passes up and is again intercepted, as

it were, by the outer side of the chamber (1). Above this point the vent for the blast is rapidly expanded as seen at (W) which is a screen, that again, under the mose quieted escape of the blast, (an effect due to the expansion given it) detains a further proportion of the flour. This flour so gathered by the chambers (Y) and (1) and the screen (W) is discharged as soon as it accumulates and packs sufficiently to fall back from its weight through the escaping blast. The part of the machine containing these chambers may be removed—for purposes of portability they are essential to the machine, but in mills the blast may be conducted to the hopper-coy room and there escape without loss of flour.

The bottom of the chamber (Q) is perforated by openings (R) for the purpose of delivering the flour, that falls in the chamber (Q), directly to the gathering chamber (S), thereby keeping the chamber (Q) in constantly good operative condition.

Fig. 2 represent the process of grinding and bolting combined.

Having thus fully clearly and exactly described the nature and operation of our joint invention we wish it distinctly understood that we do not claim the broad principle of bolting meal by an air blast as this has been imperfectly done before, but

What we do claim as new and desire to secure by Letters Patent is—

1. The application of a blast cylinder with spiral issues, as described, to the process of bolting flour or other pulverized material, by means of which during a continuous blast, the meal is consecutively thrown against the bolting cloth and so much as is not passed through at once, is given an interval of time to fall from the cloth and leave open the meshes; and is thus as it were refed to the impulse of the blast from each succeeding issue; the intermittent action at the same time causing eddies that loosen and as it were rip up the bran and flour from the cloth, separate the bran from the flour, and twirl the particles of bran in such a manner as to leave the flour free to pass through while the bran from the twirl thus given it is caused to present its broadest surface to the bolting cloth, the specking of the flour being thereby prevented and avoided; the several parts being arranged substantially in the manner and for the purpose described.

2. We also claim the insertion of a set of beaters at a suitable distance down the bolting cloth and blast cylinder, which during the bolting process shall interrupt the same at a time when the bran requires beating in order to loosen the flour from it preparatory to the further continuance of the bolting process substantially in the manner and for the purpose described.

3. We also claim the chambers (Y) and (1) by means of which the light flour, carried up by the escape of the blast, is regathered and returned to the usual gathering 5 chamber (S) substantially in the manner and for the purpose described.

In testimony whereof, we have hereunto

set our hands before two subscribing witnesses.

LEWIS FAGIN.
HENRY C. HAYMAN.
